UNITED STATES PATENT OFFICE.

JOHN H. LINDSAY, OF BROOKLYN, NEW YORK.

WATER-SEAL VACUUM-VALVE.

1,353,767.

Specification of Letters Patent. Patented Sept. 21, 1920.

Application filed February 11, 1920. Serial No. 357,849.

To all whom it may concern:

Be it known that I, JOHN H. LINDSAY, a citizen of the United States, and a resident of the city of New York, borough of Brooklyn, in the county of Kings and State of New York, have invented a new and Improved Water-Seal Vacuum-Valve, of which the following is a full, clear, and exact description.

10 This invention relates to improvements in water seal vacuum valves, an object of the invention being to prevent the escape of steam and to render the thermostatic element quickly responsive to the level of water and 15 to the contact of steam therewith so as to cause the valve to operate and maintain at all times a water seal at the valve outlet to prevent the escape of steam.

A further object is to provide a valve of 20 the character stated which is comparatively simple and inexpensive in construction, strong and durable in use.

With these and other objects in view the invention consists in certain novel features 25 of construction, and combinations and arrangements of parts as will be more fully hereinafter described and pointed out in the claims.

In the accompanying drawings—

30 Figure 1 is a view in longitudinal section illustrating my improvements;

Fig. 2 is a view in section on the line 2—2 of Fig. 1;

Fig. 3 is a view in section on the line 3—3 of Fig. 1; and

Fig. 4 is a fragmentary view in vertical section illustrating a modification.

1 represents the casing of my improved valve having a screw threaded inlet nipple 40 2 at one end which is connected by a pipe union 3 with a supply pipe or nipple 4 to be connected to the steam pipe line. The casing 1 is made with a concave bottom 5 having a central outlet opening 6 communicating with an integral outlet pipe 9, the latter having a screw threaded end 11 receiving a nipple 12 adapted to be connected to the water outlet line which may, or may not be provided with the ordinary suction 45 50 pump.

The casing 1 is made with an internal annular flange 13 and is internally screw threaded above the flange, as shown at 14, to receive a screw threaded ring 15 and a removable cap 16 is screwed onto the upper end of the casing normally closing the same.

A corrugated metal post 17 is secured at its upper end in the ring 15 and constitutes a thermostat controlling the operation of a valve 18, the latter adapted to control the 60 flow of water of condensation through the outlet 6. A disk 19 is secured in the lower end of the post or thermostat 17 and a valve stem 20 carrying the valve 18 projects through the center of the disk 19 and a ring 65 21 is fixed to the wall of the thermostat at the intermediate portion of the latter so as to strengthen the latter.

The upper end of the stem 20 is guided in its movement by a hollow cup 22 which is 70 connected by integral arms 23 with the ring 15, and a removable screw 24 is located in the ring 15 outside of the thermostat 17 and extends through the ring so that when this screw is removed, the opening 25 into which 75 it fits, will constitute a testing port for the casing outside of the thermostat.

An integral tubular extension 26 is provided on the casing 1 and projects into an inlet passage 27 formed in the nipple 2 and 80 constitutes a steam passage 28 connecting the upper portion of the casing 1 with the inlet passage 27, but it will be noted that the lower end of the tubular extension 26 extends into the inlet passage 27 so that its 85 wall constitutes a seal or cut-off when the water rises sufficiently in the casing. A wall 29 of the casing 1 adjacent the inlet passage 27 extends across the inlet passage so as to partially close the same as indicated 90 at 30, and extends lower than the lower end of the tubular extension 26. This wall or partition 29 likewise constitutes a water seal cutting off the passage of steam to the casing when the water reaches a predetermined 95 level, but permits the passage of steam through the passage 28 to the casing 1.

The parts are shown in Fig. 1 with the valve 18 opened allowing the water to escape and showing the water at a level sufficient to cut off the steam passage 28. When the water falls to a level slightly below that indicated, the steam will flow through the passage 28 into the upper portion of casing 1 and the heat of the steam will cause 100 the thermostat 17 to expand, but this operation of the thermostat will be slow because of the fact that the water at the bottom thereof is colder than the steam and the thermostat will not completely close the 105 valve until most of the water has been allowed to escape. The closing of the valve

will be gradual and the valve will be completely closed before all of the water escapes, thus preventing possibility of the loss of steam through the outlet opening.

5 To facilitate this water seal, the bottom of the casing is concaved as shown at 5, so that a certain amount of water will be maintained in the casing at all times.

Heretofore, with valves in ordinary use, 10 the thermostat element has been controlled almost entirely by the water or the level of water in contact therewith as the steam has ordinarily had communication with the upper end of the casing at all times so that 15 in reality only the lower end of the thermostatic post was caused to contract and expand and the operation of the valve was ordinarily too quick in opening and too slow in closing so that steam would escape. With 20 my improved construction steam is cut off from the casing when the water reaches the level shown in Fig. 1, and hence, the reduction of temperature in the casing 1 will cause the thermostat throughout its entire 25 length to contract opening the valve 18. When the water falls below the point indicated in Fig. 1, the steam will flow through the passage 28 to the upper end of the casing and increase the temperature in the casing 30 to cause the thermostat to expand, but, as above stated, this expansion will be relatively slow until the water falls below the end of the partition or wall 29 when the expansion will be rapid and the valve will 35 close before the entire quantity of water can escape to prevent the loss of steam.

In Fig. 4, I have illustrated a modification in which I employ a tubular extension 26' which is screwed into a cup 27' corresponding to the cup 22 and provides an extended guide for a stem 28' of a valve 29'. In other respects the construction is similar to the preferred form.

Various other slight changes may be made 45 in the general form and arrangement of parts described without departing from the invention, and hence I do not limit myself to the precise details set forth, but consider myself at liberty to make such changes and 50 alterations as fairly fall within the spirit and scope of the appended claims.

I claim:

1. A valve of the character described, comprising a casing having an outlet in its bottom, and an inlet in its side at its lower end, a valve controlling the outlet, a thermostat controlling the movement of the valve, a partition wall in said casing projecting partially across the inlet, and a steam passage connecting the inlet with the upper end of the casing and having a wall extending partially across the inlet.

2. A valve of the character described, comprising a casing having an outlet in its bot-

tom, and an inlet in its side at its lower end, 65 a valve controlling the outlet, a thermostat controlling the movement of the valve, a partition wall in said casing projecting partially across the inlet, and a steam passage connecting the inlet with the upper end of the 70 casing and having a wall extending partially across the inlet, said first-mentioned wall extending appreciably below the last-mentioned wall, said walls when the water reaches predetermined levels forming seals. 75

3. A valve of the character described, comprising a casing having a conical or sloping bottom, and an outlet port in the lowest portion of said bottom, said casing having an inlet at its side at its lower end, a valve 80 in the casing controlling the outlet port, a thermostat controlling the movement of the valve, a removable ring in the casing supporting the thermostat and the valve, a guide cup supported by the ring, a stem on 85 the valve engaging the guide cup, and a disk secured between the ends of the stem and engaging the walls of the thermostat.

4. A valve of the character described, comprising a casing having a conical or sloping 90 bottom, and an outlet port in the lowest portion of said bottom, said casing having an inlet at its side at its lower end, a valve in the casing controlling the outlet port, a thermostat controlling the movement of the 95 valve, a removable ring in the casing supporting the thermostat and the valve, a guide cup supported by the ring, a stem on the valve engaging the guide cup, a disk secured between the ends of the stem and engaging 100 the walls of the thermostat, said casing having a partition therein extending partially across the inlet and having a steam passage connecting the inlet with the upper end of the casing.

5. A valve of the character described, comprising a casing having a conical or sloping bottom, and an outlet port in the lowest portion of said bottom, said casing having an inlet at its side at its lower end, a valve in 110 the casing controlling the outlet port, a thermostat controlling the movement of the valve, a removable ring in the casing supporting the thermostat and the valve, a guide cup supported by the ring, a stem on 115 the valve engaging the guide cup, a disk secured between the ends of the stem and engaging the walls of the thermostat, said casing having a partition therein extending partially across the inlet and having a steam passage connecting the inlet with the upper end of the casing, and said steam passage having a wall also projecting partially across the inlet.

6. A valve of the character stated, comprising a casing having an outlet port in its bottom, and an inlet port in its side at its lower end, a ring removably secured in the

casing, a corrugated metal thermostat secured in the ring, a valve controlling said outlet port, disks secured to the lower end and to the intermediate portion respectively of said thermostat, a stem on the valve secured centrally in said disks, a guide cup carried by the first-mentioned ring and re-

ceiving the upper end of the stem, a removable cap closing the upper end of the casing, and said casing having a steam passage 10 therein connecting the upper end of the casing with the inlet of the casing.

JOHN H. LINDSAY.
